OCT. 12, 1880

UNITED STATES PATENT OFFICE.

WILLIAM TWEEDDALE, OF BROOKLYN, NEW YORK, ASSIGNOR TO NORTH AMERICAN IRON WORKS, OF SAME PLACE.

DESIGN FOR A FOUNTAIN.

SPECIFICATION forming part of Design No. 11,975, dated October 12, 1880.

Application filed April 12, 1880. Term of patent 14 years.

To all whom it may concern:

Be it known that I, WILLIAM TWEEDDALE, of Brooklyn, in the county of Kings and State of New York, have invented or produced a Design for a Fountain, of which the following is a specification.

This fountain is designed to be in cast-iron, and the same is represented in the accompanying photograph.

10 The top of the fountain is composed of a central standard, *a*, with a ball, *b*, spear *c*, and inverted conical leaflets *d*.

The basin *D* is polygonal. The rim is a series of arch-shaped ornaments. Below the rim 15 there are pendent arches *e*, and at the angles the rosette ornaments *e'*.

Around the standard *f*, supporting the basin *B*, there are flying buttresses *g* in ornamental open-work. There is a conical base, *h*, that is 20 ribbed, and from which rises said standard *f*.

The basin *C* is polygonal, with leaflet ornaments around the rim and pendent open-work arches *k*. There are volute ornaments *l* at the lower end of the arches, and rosettes *m* upon 25 vertical stems rising above the angles. The basin *C* is supported upon a cluster of columns, *n*, with molded caps and bases, and below the columns is a conical base, *o*, with volute leaflet ornaments, as shown.

30 The basin *B* is polygonal, having pendent open-work arches *r* beneath the rim, which rim is made as a series of panels with scroll and star shaped ornaments. There are sphinx figures *s* at the angles, and rosette ornaments 35 *t* above the centers of the arches. The basin *B* is supported upon a base ornamented with panel-work at *u*, moldings, columns, and checker-work at *v*, wings *w*, that extend out radially at the bottom of the base and are 40 molded, and these wings support ornamental posts *x*, with globular ornaments, and the open-work flying buttresses *y*, with scroll-work

and leaflet ornaments, as shown, complete the design.

This design, as a whole, is beautiful in appearance, and rendered still more so by the water when it is falling upon the different ornaments and dripping from them.

It will be apparent that smaller fountains may be made by the use of one or more of the basins with the ornamental parts pertaining thereto.

I claim as my invention—

1. The design of the shape and configuration of the upper basin, *D*, rim, pendent arches *e*, 55 and rosettes *e'*, substantially as shown.

2. The design of the basin *C*, with its rim, pendent arches, rosettes, central cone, and flying buttresses, substantially as set forth.

3. The design of the shape and configuration 60 of the basin *B*, with its rim, pendent arches, rosettes, and sphinx, substantially as set forth.

4. The design of the ornamental base and columns beneath the basin *C*, substantially as 65 represented.

5. The design of the fountain-base, consisting in the body with panels and moldings, the molded wings, the posts with globular ornaments, the flying buttresses, and the scroll-ornaments, substantially as set forth and 70 shown.

6. The design of the fountain, consisting of the basin *D*, ornamented as shown, the basins *C* and *B*, and ornamental connecting-columns, and the fountain-base, flying buttresses, moldings, wings, rosettes, pendent arches, and other ornaments to the respective parts, substantially as described and represented.

75 Signed by me this 8th day of March, 1880.

WILLIAM TWEEDDALE.
